UNITED STATES PATENT OFFICE

JOSEPH A. V. TURCK, OF WILMETTE, ILLINOIS, ASSIGNOR TO FELT & TARRANT MANUFACTURING COMPANY, OF CHICAGO, ILLINOIS, A CORPORATION OF ILLINOIS

CALCULATING MACHINE

Application filed October 8, 1923. Serial No. 667,277.

This invention relates to calculating machines of the ordinal key type and its object is to provide an improved mechanism for preventing errors in calculating operations, which may arise from a partial key stroke; the invention comprehends the provision of means individual to the respective orders of keys for notifying the operator of a partially depressed key, for example, by locking the cancelling crank against operation, whenever a partial key stroke occurs, with the result that the operator is unable to cancel the machine, until the partial stroke of the mis-manipulated key has been completed. The error-prevention mechanism of the invention operates independently of the usual keyboard locking mechanism of this class of machines, and is controlled by the segment lever or column actuator of the order in which a partial key stroke has occurred, independently of the column actuators of any other orders. In this respect, it differs from the keyboard locking mechanism wherein the locking action is universal, i. e., throughout the entire keyboard of the machine, with the exception of the mismanipulated key. Moreover, the locking of the cancelling or zeroizing mechanism is effected even though a segment lever be erroneously depressed not far enough to add "one" to the corresponding accumulator. Consequently, the invention provides a valuable safeguard, additional to the keyboard locking mechanism, particularly in conjunction with units keys of the various orders which may be partially depressed without actuating the keyboard locking mechanism. The invention is thus especially useful, though not restricted to calculating machines designed for working in terms of British currency, in which machines the third order comprises only a single units key employed to accumulate tens of shillings.

The invention is moreover applicable for use in connection with calculating machines of the key-driven multiple-order type, and, in the present embodiment, is illustrated in a machine of the general type of the well known "duplex comptometer", the general character of which is exemplified in the United States patents to Dorr E. Felt, No. 762,520 and

762,531, dated June 29, 1904; No. 1,028,344, dated June 4, 1912; No. 1,066,096, dated July 1, 1913; No. 1,072,933, dated September 9, 1913; the patent to Kurt F. Ziehm, No. 1,110,734, dated September 15, 1914 and my prior Patents, Nos. 1,357,747 and 1,357,748, dated November 2, 1920.

In addition to the general objects recited above, the invention has for further objects such other improvements or advantages in construction and operation as may be found to obtain in the structures and devices hereinafter described or claimed.

In the accompanying drawings, forming a part of this specification, and showing, for purposes of exemplification, a preferred form and manner in which the invention may be embodied and practiced, but without limiting the claimed invention to such illustrative instance or instances:

Figure 1 is a vertical sectional elevation taken at the extreme right hand side of a calculating machine of the multiple-order key-driven type, in which the present improvements are embodied;

Fig. 2 is another vertical sectional elevation taken farther to the left than that of Fig. 1; and

Fig. 3 is a plan view of a calculating machine designed for operation in terms of British currency.

The same characters of reference indicate the same parts in each of the several views of the drawings.

In its present embodiment, the invention is incorporated in a calculating machine of the multiple-order key-driven type, such as the well known comptometer disclosed in the prior United States Letters Patent hereinbefore referred to. As the details of construction of this type of machine may be readily understood from these United States patents, a brief description of the general features of this type of machine, and such parts as are directly concerned with the operation of the present improvements, will be sufficient for an understanding of this invention.

The various instrumentalities of the calculating machine are supported by a frame mounted on the base 21 of a casing, said

frame consisting essentially of side skeleton plates 22 and intermediate skeleton plates 23 disposed between the various actuating mechanisms of the several orders of the machine, 5 and all tied together at suitable points by transverse tie rods 24. According to the present type of the machine a number of columns of nine keys each are provided for the "pounds" columns L, one key for the tens 10 of "shillings" column T, nine keys for the "shillings" column S and eleven keys for the "pence" column D. In the event that the invention is applied to computation according to the decimal system, for example, for 15 use in calculation in United States currency, every column will have nine keys. Each key is indicated by the reference character 25; there is a column of keys for each numeral wheel; and also the actuating mechanisms 20 and attendant parts interposed between a column of keys and its corresponding numeral wheel. Each column of keys 25 forms a part of an actuating mechanism for transmitting through the accumulator mechanism 25 to its numeral wheel an amount of travel proportional to the particular key operated.

The actuating mechanism for each column of keys and the corresponding numeral wheel includes a column actuator in the form of a 30 segment lever 26 pivoted at the rear of the machine and depressed for distances determined by the numerical value of the key operated. Each key is provided with a stem 27 extending down and bearing upon the corresponding column actuator 26. The key at 35 the extreme front of the machine, being farther from the pivotal axis of the column actuator than the key at the extreme rear of the machine, moves the column actuator 40 through a lesser arc than does the key last mentioned.

The column actuator 26 of each order or 45 column of keys is adapted to impart calculating movement to an accumulator and, for such purpose, is provided at its forward end with a rack 28 which meshes with an accumulator pinion 29. The pinion 29 of each order forms a part of an internal ratchet mechanism, not herein described or shown in 50 detail, but fully set forth in the prior patents hereinabove mentioned; such ratchet mechanism becomes effective during the upstroke of the column actuator to clutch the pinion 29 to a train of gearing 33 extending to the 55 numeral wheel or registering wheel 38. During the downstroke of the column actuator, the ratchet mechanism moves idly, without transmission of calculating movement by the gear train to the numeral wheel 38. However, upon the return or upward movement 60 of the column actuator, a clutching operation is effected so that the gear train rotates the numeral wheel 38 to register a numerical value corresponding with the actuated key. 65 Carrying mechanism is co-operatively com-

bined with each ordinal accumulator mechanism for the purpose of actuating the accumulator mechanism of the next higher order of the machine whenever a carry is to go over from a lower order. The carrying mechanism provides for simultaneous depression of keys and delivery of column actuator impulses in two or more adjacent orders, as explained in the said prior patents hereinbefore mentioned. However, any carrying impulses released from a lower one of said orders will not be actually delivered to the next higher of said orders until the column actuator movement of such higher order is 70 complete. The operation of permitting simultaneous key-driven actuation of a plurality of column actuators in adjacent orders, the strokes overlapping each other in any manner, is the action known as "duplexing". 75

Such is, in brief outline, the manner in which prime actuations and carrying impulses are imparted to the accumulator mechanisms in the duplex comptometers of the above mentioned patents. It will also be understood that these actuating mechanisms 80 are associated with various stop mechanisms set forth in the said patents, to limit the movements imparted to the accumulator mechanisms by the prime actuations and carrying impulses; all of these stop mechanisms 85 are shifted variously into and out of their various stop positions to impose additional restrictions to the movement of the carrying devices and to the prime actuations of the accumulators. 90

There is also provided a cancelling or zeroizing mechanism for clearing the machine or cancelling, that is, for returning the registering wheels and other parts to the zero positions. Briefly stated, the zeroizing operation 100 is accomplished by disconnecting the connections between the registering wheels 38 and the actuating devices so that, while retaining the various above mentioned stop devices in their normal relations to the accumulator 105 mechanisms, the stored power in the carrying springs may give to the numeral wheels backward rotations, so as to move them rearwardly from the divers positions they may occupy and stop them when they arrive individually 110 at zero positions. 115

The shaft 37 of the numeral wheels is mounted in bearings fixed in the frame of the machine, as is likewise the shaft 30 of the ratchet mechanism and gearing and the shaft 35 of the gears 34 of the gear train 33. In order to effect detraining or disengagement of the carrying spring winding gears (see Patent No. 1,357,748) from the gearing on the shaft 30, the shaft 50 of the carrying spring winding gears is carried by a swinging frame, indicated generally at 64. The frame 64 is adapted to have a slight outward pivotal movement on an axis coincident with the shaft 35. As the swinging frame carries 120 125 130

with it the shaft 50 of the carrying spring winding gears, the latter are disconnected from the gearing on the shaft 30, whenever said swinging frame 64 has an outward pivotal movement on its axis. In the present embodiment of the invention, the swinging frame is detained in such gear detraining position, after a cancelling operation has been effected, until a key 25 has been depressed to effect a further operation of the accumulator mechanism whereupon the swinging frame is again restored to position for entraining the carrying spring winding gears with the gearing of the shaft 30.

The following instrumentalities are included in the mechanism for moving the swinging frame to detrain, as above described, and to permit the carrying springs to return the registering wheels to zero positions. As shown in Fig. 1, an operating handle or lever 71, hereinafter termed the "cancelling crank" is pivoted at the right hand side plate 22 of the fixed frame. A segment 72 is fixed to this lever, and pivoted to said segment 72 is a link 73 which, in turn, is pivoted to a depending lever 74 that is pivoted at 75 on the fixed frame. The lower end of said lever 74 is pivotally connected by means of a short link 76 with an arm 77 rotatably mounted on a transverse shaft 78 that is itself journaled in the fixed frame. The arm 77 is provided with an engaging face 79 adapted to contact with a second arm 80 fixed on the shaft 78. The operation of this construction is as follows: When the parts are in the relative positions indicated in Fig. 1, a short swinging movement of the cancelling crank 71 toward the left will, through the segment 72, link 73, lever arm 74, short link 76, arm 77 and rocker arm 80 impart a short rocking movement to the shaft 78 in a counter clockwise direction as viewed in Fig. 1, and such counter clockwise rocking of the shaft 78 is effected through the instrumentality of connections fully described in said Patent No. 1,357,748, to swing the arm 64 upwardly and to detrain the carrying spring winding gears from the gearing on the shaft 30. The action of detraining the gearing releases the carrying springs, permitting them to unwind and to turn the several registering wheels reversely from their various positions to zero positions. The unwinding of the carrying springs is terminated by stops which are projected in operative position on arrival of the various registering wheels at zero, by means of devices and in the manner shown and described in my said prior patent.

The present invention provides means individualized to the several or any of the orders of the machine for preventing errors in calculating operation, by locking the cancelling crank against operation, whenever a key has been partially depressed and released, even though the key be moved not far enough

to add "one" in the corresponding accumulator mechanism. After a key thus partially depressed has been moved to complete its stroke, the cancelling mechanism is again released for operation. The error prevention means of the invention operates entirely independent of and without effect upon the usual key board locking mechanism of a standard "duplex comptometer", and provides an additional check against errors, which is especially useful in conjunction with the units keys, inasmuch as the "units keys" have not sufficient capacity to operate the keyboard locking mechanism. An important application of the invention is therefore in machines which compute in British currency, as such machines in the tens of shillings order are provided with one, a "units" key. As shown in Fig. 2 there is provided on the zeroizing shaft 78 a zeroizing stop arm 101, preferably, for each order of the machine. Pivot ed on the rod 102 in each order of the machine is a locking dog 103, to a depending lip 104 of which is attached a spring 105. The spring extends to and is attached at 106 to a fixed portion of the frame, and, when the dog is released, throws it and its locking tooth 107, so that the locking tooth engages the zeroizing stop arm 101 of the corresponding order and prevents movement of the shaft 78 to effect a zeroizing operation. This happens whenever a key in that order, for example, the "units" key has been partially depressed and released, even though not moved sufficiently to add "one". The release of the dog is effected by a lock releasing roll 108 mounted on the segment lever 26 of the corresponding order and moved by said segment lever beneath the arm 109 of the dog, whenever the segment lever remains in lowered position from a partial depression and release of a key. The operation of a key for its full stroke results, of course, in an immediate rising of the segment lever, so that the dog 103 will be shifted to inoperative position by the roll 108 engaging under the hook of the arm 109. The locking action of the dog is thus not effective during correct key manipulation and, may also be released after mismanipulation, by operating the mismanipulated key for its full stroke.

The calculating machine described in the above specification embodies various other instrumentalities and devices which need not be herein described, for the reason that they are fully set forth in the prior patents above mentioned.

The term "cancelling crank", wherever employed in the ensuing claims, has been adopted for convenience and is not to be construed strictly, but includes broadly, in addition to the specific disclosure of the drawings and description, cancelling or zeroizing mechanisms, whether manually or power operated.

The invention as hereinabove set forth is

embodied in a particular form of construction, but may be variously embodied within the scope of the claims hereinafter made.

I claim:

5. In a calculating machine, in combination: ordinal keys; registering wheels; key-driven actuating devices for said registering wheels, including ordinal column actuators; cancelling mechanism; and ordinal locking 10 dogs interposed between said column actuators individually and said cancelling mechanism and rendered operative to block movement of the cancelling mechanism upon partial depression of a corresponding ordinal 15 key for any distance insufficient to register the numerical value of the key on the corresponding registering wheel.

2. In a calculating machine, in combination: keys; registering wheels; key-driven 20 actuating devices for said registering wheels, including ordinal column actuators; cancelling mechanism; and locking dogs interposed between said column actuators individually and said cancelling mechanism and 25 normally held in inoperative position by said column actuators and rendered operative to block movement of the cancelling mechanism upon partial depression of a corresponding key for any distance insufficient to register 30 the numerical value of the key on the corresponding registering wheel.

3. In a calculating machine, in combination: keys; registering wheels; key-driven actuating devices for said registering wheels, 35 including ordinal column actuators; cancelling mechanism; and spring actuated locking dogs interposed between said column actuators individually and said cancelling mechanism and controlled by partial depression 40 of a corresponding key for any distance insufficient to register the numerical value of the key on the corresponding registering wheel, to block movement of the cancelling mechanism and controlled by complete depression 45 of such key to permit movement of the cancelling mechanism.

4. In a calculating machine, in combination: ordinal keys; registering wheels; key-driven actuating devices for said registering 50 wheels, including ordinal column actuators; cancelling mechanism; and ordinal locking mechanism individual to each order of the machine and controlled by the corresponding ordinal keys and individual column actuators to render inoperative the cancelling 55 mechanism upon partial depression of any ordinal key.

5. In a calculating machine, in combination: keys; registering wheels; key-driven 60 actuating devices for said registering wheels, including ordinal column actuators; cancelling mechanism; and locking mechanism controlled by the corresponding keys and individual column actuators and movable into 65 locking position on initial movement of the

column actuator to render inoperative the cancelling mechanism upon partial depression of any key.

6. In a calculating machine, in combination: ordinal keys; registering wheels; key-driven actuating devices for said registering wheels, including ordinal column actuators; cancelling mechanism; and ordinal locking mechanism for said cancelling mechanism, 70 said locking mechanism being rendered operative by an individual ordinal column actuator upon mismanipulation of a corresponding ordinal key and rendered inoperative by the correct manipulation of the mismanipulated key. 75

7. In a calculating machine, in combination: keys; registering wheels; key-driven actuating devices for said registering wheels, including ordinal column actuators; cancelling mechanism; and means controlled by 80 the individual ordinal column actuators responsive to partial depression of any key for rendering inoperative said cancelling mechanism and responsive to complete depression of any partially depressed key for rendering 85 operative said cancelling mechanism. 90

8. In a calculating machine, in combination: keys; registering wheels; key-driven actuating devices for said registering wheels, including ordinal column actuators; cancelling mechanism; and means controlled by 95 the individual ordinal column actuators and operable on initial movement thereof and responsive to partial depression of a units key for rendering inoperative said cancelling 100 mechanism.

9. In a calculating machine, in combination: a plurality of ordinal keys; registering wheels; actuating devices, including ordinal column actuators for said registering wheels rendered operative upon movement of the keys; a cancelling crank; a cancelling crank lock; and means individual to each order of the machine, controlled by operation of the column actuators in the individual orders 105 for moving said lock into locking position on initial movement of a column actuator and responsive to mismanipulation of any key for rendering operative said cancelling 110 crank lock. 115

10. In a calculating machine, in combination: a plurality of keys; registering wheels; actuating devices for said registering wheels, including ordinal column actuators; a cancelling crank; a cancelling crank lock; and means controlled by the individual ordinal column actuators for moving said lock into locking position on initial movement of a column actuator and responsive to mismanipulation 120 of any key for rendering operative said cancelling crank lock. 125

11. A calculating machine provided with keys, registering wheels, actuating devices for said registering wheels, including ordinal column actuators, and zeroizing mechanism, 130

combined with means, operable on initial movement of a column actuator and controlled by mismanipulation of any key and its ordinal column actuator, for locking said zeroizing mechanism.

12. A calculating machine provided with keys, registering wheels, actuating devices for said registering wheels including ordinal column actuators, and zeroizing mechanism, combined with means individual to each order of the machine and controlled by the individual ordinal column actuators, responsive to partial depression of a "units" key, for locking said zeroizing mechanism.

15 In testimony whereof I have hereunto set my hand.

JOSEPH A. V. TURCK.
